CLAIM

The ornamental design for a bicycle frame, as shown
and described.

DESCRIPTION

FIG. 1 is a perspective view of a bicycle frame showing
our new design, it being understood that the broken
lines are for illustrative purposes only and form no part
of the claimed design;

FIG. 2 is a side elevational view thereof, the opposite
side being identical thereto;

FIG. 3 is a top plan view thereof;

FIG. 4 is a bottom plan view thereof;

FIG. 5 is a front elevational view thereof;

FIG. 6 is a rear elevational view thereof.
